UNITED STATES PATENT OFFICE.

RAY ADNA NORTH, OF GREEN BAY, WISCONSIN, ASSIGNOR TO E. PAYSON SMITH,
OF GREEN BAY, WISCONSIN.

PULP DEHYDRATOR.

Application filed July 1, 1921. Serial No. 481,821.

To all whom it may concern:

Be it known that I, RAY A. NORTH, a citizen of the United States of America, residing at Green Bay, in the county of Brown 5 and State of Wisconsin, have invented certain new and useful Improvements in Pulp Dehydrators, of which the following is a specification.

The present invention relates to improvements in that type of machine which is specially adapted to separate matter from liquid.

The object of my invention is to provide a simple, but efficient machine for thickening, 15 or dehydrating sewerage, pulp and the like, at a minimum cost;

And with this and other objects in view my invention consists of the parts and combination of parts as will be hereinafter more 20 fully set forth.

In the drawing

Figure 1 is a front elevation of the dehydrating machine embodying my invention.

Figure 2 is an end elevation of Figure 1, 25 parts being broken away and parts shown in section.

The reference numeral 1 designates a casing of any suitable construction having top, side and end walls. Within the casing I 30 mount an arcuate pressure plate 2, which rests on the bottom of the casing but is otherwise spaced from the walls of the casing except at the end walls of the casing with which the said plate abuts. It will be noted 35 that the inlet end 3 of the pressure plate is in a lower horizontal plane than the outlet end 4, as clearly shown in Figure 2 of the drawing.

The discharge apron 5 is swingingly 40 mounted on the discharge end 4 of the pressure plate 2, and is adjustable to various angles according to the desires of the operator. This apron is adapted to guide the dehydrated pulp and the like into the receiving trough 6, but in the event that it is desired 45 to direct the dehydrated pulp through a pipe 7 I provide the apron with a port intermediate its edges, which is temporarily closed by the plug 8 so that when the apron 5 is swung to an upward position the pulp will be discharged through the port in the apron when the plug 8 is removed therefrom.

The drum 9 is of spider construction and 55 is provided around its periphery with a se-

ries of wire mesh panels 10, which are secured in position by any suitable means, such as the strips 11. The drum is provided with a sprocket wheel 12, which is connected by means of a drive chain 13 to a suitable pinion 14 keyed to the shaft of the power wheel 15. Any suitable driving mechanism may be substituted for the one shown.

16 is an inlet pipe at the rear of the machine, which is adapted to deliver the material to be treated in the casing to a point above the edge 3 of the pressure plate 2, at which point the material to be treated drops into the space between the pressure plate 2 and the periphery of the drum 9.

It will be noted that the drum 9 is revolvably mounted within the casing 1 with its periphery eccentric with respect to the pressure plate 2 so that there is formed between the periphery of the drum 9 and the pressure plate 2, a channel or space which gradually narrows toward the outlet end 4 of the pressure plate 2, at which point the passage way 16 is of less cross sectional area than at any other point.

A spray-pipe 17 is suspended within the drum 9 and connected with the supply pipe 18, said spray-pipe being located in close proximity to the periphery of the drum and positioned in a horizontal plane slightly above the horizontal plane of the receiving edge 3 of the pressure plate 2, as clearly shown in Figure 2. A spray pipe 19, connected with the supply pipe 18, is positioned outside of the drum near the periphery thereof in a horizontal plane above the horizontal plane of the outlet edge 4 of the pressure plate. 20 is a liquid outlet pipe in connection with the interior of the machine, whereby liquid extracted from substance under treatment may readily escape from the machine.

In the operation of the machine the pulp, sewerage, and the like, to be dehydrated is introduced into the machine through the inlet pipe 16 and travels upwardly until it reaches a point above the inlet edge 3 of the pressure plate 2, at which point it drops onto the pressure plate 2 between the periphery of the drum 9 and the pressure plate. Should any of the material have a tendency to rise above this point of inlet at the top edge 3 of the pressure plate 2 the spray or blast from the pipe 17 through the wire mesh 10 of the drum forces the material under treatment to

flow into the passageway 16 and at the same time thoroughly cleanses the meshes of the wire panels 10 previous to their passing below the edge 3 of the pressure plate 2, so that 5 these meshes are always free when working in conjunction with the pressure plate 2, to admit of the passage of liquid there-through.

The drum is provided on its periphery with a series of stock pushers 21 which pushers 10 push the stock or material under treatment through the passageway 16 and prevent the stock or material under treatment from becoming dry, and also have a tendency to roll the stock while under treatment, 15 thereby preventing it from packing and breaking the wire panels 10.

As the pulp or material under treatment passes forwardly through the passageway 16 it goes into the gradually narrowing outlet portion of the passageway and is compacted to such extent that substantially all 20 of the moisture is compressed therefrom by the time that the stock arrives at the outlet edge 4 of the pressure plate 2, whereupon continued movement of the parts brings the dehydrated material above the apron 5 and it flows on said apron and is delivered into the receptacle 6 or the outlet pipe 7 as the operator may elect. Should 25 the material under treatment have a tendency to stick to the periphery of the drum 9 above the apron 5 the spray from the pipe 19 being directed in a downwardly inclined angle as indicated, will strip the dehydrated material from the periphery of the drum and cause it to flow upon the apron 5, and at the same time will cleanse the 30 meshes of the wire panels 10, thereby keeping them clear for efficient work in dehydrating the material under treatment.

Surplus water or liquid from the material under treatment passes out of the machine through the pipe 20.

From the above it will be seen that the 45 machine is easily kept clean for efficient action, that it has a maximum capacity, and is economical in operation. In actual practice the machine has proven highly efficient.

What I claim is:

50 1. In a pulp dehydrator the combination with a casing, and an imperforate arcuate pressure plate therein, of a drum having a perforated periphery and revolvably mounted in said casing with its periphery eccentric to said plate, whereby a comparatively wide mouth is formed at one side of the dehydrator between the drum and plate and a comparatively narrow pulp exit is formed at the other side of the dehydrator, an inlet pipe in communication with the said mouth, a spray pipe within the drum adapted to direct a spray outwardly through the perforated periphery of the drum above the said mouth, and a spray pipe outside of the drum adapted to direct a spray

through the perforated periphery into the drum above the outlet between the drum and plate, and an apron to receive the dehydrated pulp as it falls from the periphery of the drum of said outlet and direct 70 it to a suitable receptacle.

2. In a pulp dehydrator of the character described, the combination with an arcuate pressure plate, of a drum eccentrically mounted with respect to the plate, the periphery of the drum being perforated, a water spray pipe within the drum, and a water spray pipe outside of the drum. 75

3. In a pulp dehydrator of the character described, the combination with an arcuate pressure plate, of a drum revolvably mounted and eccentrically mounted with respect to said plate, the periphery of the drum being perforated, a stationary water spray pipe within the drum adapted to direct a spray from the inside through the perforated periphery of the drum, and a spray pipe outside of and adapted to direct a spray through the perforated periphery 80 into the drum. 90

4. In a pulp dehydrator of the character described, the combination with an arcuate pressure plate, of a drum revolvably mounted and eccentrically mounted with respect to said plate, the periphery of the drum being perforated, a stationary water spray pipe within the drum adapted to direct a spray from the inside through the perforated periphery of the drum, and a spray pipe outside of and adapted to direct a spray through the perforated periphery 95 into the drum, and a water outlet pipe communicating with the interior of the drum. 100

5. In a pulp dehydrator of the character described, the combination with an arcuate pressure plate, of a drum revolvably and eccentrically mounted with respect to said plate, the periphery of the drum being perforated, a stationary spray pipe within the drum, adapted to direct a spray from the inside through the periphery of the drum, a delivery apron to receive the dehydrated pulp from between the periphery of the drum and said plate, and a spray pipe positioned outside of the drum above 110 said apron and adapted to direct a spray 115 into the drum through the periphery of the drum.

6. In a pulp dehydrator of the character described, the combination with an arcuate pressure plate, of a drum revolvably and eccentrically mounted with respect to said plate, the periphery of the drum being perforated, a stationary spray pipe within the drum adapted to direct a spray from the inside through the periphery of the drum, a delivery apron to receive the dehydrated pulp from between the periphery of the drum and said plate, and a spray pipe positioned outside of the drum above 120 said apron and adapted to direct a spray 125 into the drum through the periphery of the drum. 130

apron and adapted to direct a spray into the drum through the periphery of the drum, and a water outlet pipe communicating with the interior of the drum.

5 7. In a pulp de-hydrator of the character described, the combination with an arcuate pressure plate, of a drum revolvably and eccentrically mounted with respect to said plate, the periphery of the drum being perforated, a stationary water spray within the drum adapted to direct a spray from the in-

side through the periphery of the drum, a delivery apron to receive the de-hydrated pulp from between the plate and drum, a spray pipe positioned outside of the drum and adapted to direct a spray into the drum above the said apron, and a series of pulp pushers projecting from the periphery of the drum. 15

In testimony whereof I affix my signature. 20

RAY ADNA NORTH.
